UNITED STATES PATENT OFFICE

GEORGE O. FROSTAD AND JAMES E. ANNEN, OF MILWAUKEE, WISCONSIN, ASSIGNEES TO
THE NATIONAL PAPER CAN COMPANY, OF MILWAUKEE, WISCONSIN, A CORPOR-
ATION OF WISCONSIN

FEED FOR DISKS OR THE LIKE

Application filed April 6, 1928. Serial No. 267,879.

This invention relates to feeds for disks of paper or the like, and is herein particularly described as applied to a paper can making machine, such as disclosed in our copending 5 application, Serial No. 267,878, filed April 6, 1928. In that application, there is described means for punching disks from a paper strip, flanging the same, and forcing them into the open end of a preformed can body. The 10 can body and the flange are thereafter rolled together to form a joint.

In certain cases, it is desired to have the printed matter appear on the disk forming the can end. It is difficult to insure continuous 15 registry of the punching die with printed matter appearing at intervals on a paper strip, and it is therefore desirable to preform and print the disks and feed them individually to the machine. In other cases, it may 20 be desired for various reasons to feed unprinted disks to the machine.

The disks employed are relatively thick and stiff as compared with ordinary paper. They are usually of relatively heavy stock, im- 25 pregnated with paraffin. Their edges are generally slightly burred, due to the die cutting operation. The disks therefore tend to resist sliding of one over the other, thus making ordinary feed devices impracticable. The 30 disks are frequently warped or wrinkled.

We provide a feed mechanism wherein the disks are supported in a stack. The feeding is from the bottom of the stack so that the supply of disks may be renewed without stop- 35 ping the machine. We provide suction means for drawing the bottom disk against the supporting plate, thereby eliminating the irregularities in feeding which ordinarily arise from the wrinkled condition of the material.

40 We preferably employ a reciprocating pusher for sliding the bottom disk out from under the stack. Means is also provided for riffling the stack so as to remove any tendency of the disks to adhere. This tendency arises 45 from the burs formed on the disk edges by the punching operation. We employ a separating finger spaced far enough from the support to permit passage of the bottom disk in the stack, but holding the remainder of the 50 stack in check. Supplemental means is pro-

vided beyond the fingers for feeding the disks forward. This supplemental means preferably comprises a pair of constantly driven feed rolls.

55 Regardless of whether a disk feeding device is employed in connection with a can making machine or in some other combination, it is generally impossible to employ feed means which will carry the disk to its ultimate destination. We therefore provide for feeding one disk forward by engaging it with a succeeding disk. In this manner, the disk fed may be spaced from the disk consuming device, thereby making it easy to adjust. At 60 the same time, there is no necessity for complicated mechanism for advancing the disks to their final position.

65 Since one disk is fed forward by another, we provide for varying the position of the disk feeding device relative to the disk consuming device. It is desirable to maintain a substantially continuous supporting surface along the entire path of the disks, and we therefore employ a pair of supporting members having interengaging fingers. 70 These fingers may be moved into or out of engagement with one another in varying amounts, so as to provide a substantially smooth and continuous supporting table of 75 varying length. A top guide is provided for holding the fed disks against the table so as to insure that the edges of the leading disk and the one which is pushing it forward will not overlap. This top guide preferably ex- 80 tends from the feed rolls to the disk consuming device and is therefore made adjustable as to length. It is further provided with yielding means whereby it exerts a slight pressure on the top of the disk.

85 The disk feeding device is arranged to be driven from the disk consuming device, so that the two units operate in timed relation.

90 While we have described the feeding mechanism in connection with paper disks, it is to be understood that it is applicable for use 95 in connection with other material and with machines other than can forming machines, and that such uses are contemplated without departing from the scope of the invention.

100 In the accompanying drawings which illus-

trate the present preferred embodiment of our invention,

Figure 1 is a sectional view of a feeding machine embodying our invention;

5 Figure 2 is a plan view thereof taken along the section line II—II of Figure 1;

Figure 3 is a side elevation of the machine shown in Figure 1;

10 Figure 4 is a view partially in elevation and partially in section, taken along the section line IV—IV of Figure 3;

Figure 5 is a plan view taken along the section line V—V of Figure 3; and

15 Figure 6 is an enlarged sectional view of a portion of the feeder mechanism shown in Figure 1.

We provide a feeding mechanism A for feeding paper disks to a cam driven plunger B for shaping and inserting them into cylindrical can bodies, and a vacuum system C for controlling the movement of the disks. Feeder rollers D may supply a strip of paper to the plunger B from which disks are punched. The movement of the feeding mechanism A, 20 plunger B and the rollers D are coordinated by an interconnecting mechanism E.

The feeding mechanism A for feeding paper disks to the plunger B comprises a base 2, supported in part by a standard 4, 30 and in part by a plate 5, secured by bolts 6 to the plunger mechanism B. Standards 7 are adjustably mounted in slots 8 in the base 2 and cooperate with a standard 9 for supporting a stack of paper disks 10. The standard 9 is adjustably supported on a frame 11, carried by the base 2 by a set screw 12. The lower end of the standard 9 is spaced from the base 2 a sufficient distance to permit but a single disk 10 to pass therebeneath at any 35 time into engagement with feed rollers 13, mounted in the frame 11.

A rack 14 is mounted in a slot 15, centrally disposed at the center of the base 2. The rack 14 carries a plate 16, that engages the 45 outer edge of the lower disk 10 during the feeding operation. As is shown in Figure 2, the rack 14 may be provided with a plurality of plates 16' and 16'', depending upon the diameter of the disks 10. The plate 16 having a sloping portion 17 is secured to the rack 14 by screws 18.

Referring to Figure 6, the plate 16 engages the rear edge of the lower disk 10 and advances it during the operation of the feeding mechanism A, at which time the plate 16 slides beneath the stack of disks 10 and riffles them, thereby freeing the lower disk 10 from the stack preparatory to a subsequent feeding operation.

50 The base 2 is provided with a chamber 19 that surrounds the slot 15, to which a pipe 20, constituting a portion of the vacuum system C, is attached by branch pipes 21. The chamber 19 is covered by a plate 22, that is held 55 in position by screws 24. The plate 22 is pro-

vided with a plurality of openings constituting ports disposed above the chamber 19. The ports 23 permit a gripping action of the disks 10, as they move along the base 2, thereby flattening them and holding them tightly in position to be engaged by the rollers 13.

At one end of the chamber 19, there is disposed a suction gripper 25, constituted by a block 26, that is upwardly biased by a spring 27, in order that the outer face of the block 26, which is provided with a port 28, shall engage the advancing disk and draw it firmly against the plate 22, in order that a positive engagement may be made between it and the rollers 13. As the edges of the disks 10 may carry burrs, it is important that provision be made for insuring that the advancing edges of the disks 10 shall lie snugly against the plate 22, as a faulty engagement of the disks 10 by the rollers 13 might result in the deforming of the edges of the disks and in destroying the synchronism of the feeding mechanism with respect to the plunger.

The rack 14 is actuated by a pinion 29, carried by a shaft 30, that is, in turn, actuated by a pinion 31, engaging a rack 32, slidably mounted in the base 2 and connected to a link 34, constituting a portion of the interconnecting mechanism E. Accordingly, as the link 34 is moved forwardly and backwardly, the plates 16 and 18 are given a reciprocating motion that advances the lowest disk 10 and riffles the remaining disks preparatory to the next advancing stroke of the plate 16.

Referring to Figures 3 and 4, the feed rollers 13 are continuously driven by a chain 35, connected to the lower roller 13, provided with a gear 36, meshing with a gear 37 on the upper roller.

A tensioning device 38, having a sprocket 39, is mounted on the plunger mechanism B. The tension on the rollers 37 is controlled by springs 40 and thumb screws 41, carried by the frame 11.

As the disks 10 are advanced to the rollers 13, they pass therethrough and are engaged by a guide 42 and supported by an adjustable table 44, the position of which is controlled by a spring 45, a set screw 46 and a lug 47, carried by the plunger B. The distance between the table 44 and the guide 42 may be varied in accordance with the depth of the disks 10. As the disks 10 are moved over the table 44 in accordance with the movement of the disk through the rollers 13, the table 44 is adjusted in accordance with the diameter of the disks, and to insure that a disk 10 is moved over the table 44 into the plunger mechanism B in synchronism with the movement of a new disk 10 through the rollers 13. For this purpose, the guide 42 is provided with slots 48 and bolts 49, and the table 44 is carried by rods 50, the position of which is

controlled by set screws 51. The base 2 is provided with a plurality of outwardly projecting fingers 52 that mesh with corresponding fingers 53 carried by the table 44, to accommodate for the adjustment of the position of the table 44 relative to the base 2 and to provide a continuous surface over which the disks may travel.

The plunger mechanism or cap forming head B comprises an outer barrel 54, carrying a die 55, at its bottom for stamping disks from paper when fed from the rollers D, as is described in our copending application.

Within the barrel 54 is mounted a sleeve 56, carrying a punch 57 that cooperates with the die 55 for punching paper disks from paper fed by the rollers D. Within the sleeve 56, a plunger 58 is mounted that terminates in a ram 59, having a stripper 60 carried by a rod 61 extending longitudinally thereof. A spring 62 normally biases the stripper 60 in a downward position with respect to the plunger 58. The sleeve 56, plunger 58 and rod 61 are all actuated by several rollers 64 positioned in the grooves in the cam faces 62.

The construction of the several face cams 62 and their sequence of operation is fully described in our copending application and the description is not repeated in the present application, since the details thereof constitute no part of the present invention except as the operation of the plunger mechanism B effects the operation of the feeding mechanism A.

In the operation of the plunger mechanism B, the sleeve 56 is moved downwardly to strike out a disk of paper within the die 55. The disk is then pressed into the body of a can held by a mandrel on an endless conveyor. After the paper disk has been driven into the can body, the ram 59 is withdrawn and the can is held by the stripper 60. After the ram 59 has been retrieved to its initial position, the stripper 60 is withdrawn by the action of the spring 62.

A feeding mechanism D comprises rollers 65 and adjustable rollers 66, each of which has a cam surface for feeding a continuous strip of paper to the plunger mechanism B when it is desired to punch out the disks during the operation of the plunger mechanism. For certain classes of work, it is difficult to secure perfect registry of the die 55 with printed matter on the paper being fed to the plunger, and under such circumstances, it may be desirable to feed the preshaped disks to the plunger mechanism B by the feeding mechanism A. The roller 65 is driven by a chain 66 from a pulley 67, carried by a shaft 68 that drives the cam faces 62. A tensioning device 69 is provided for the chain 66. The link 34 is eccentrically mounted on to the roller 65, and accordingly the driving mechanism for the plunger B actuates the feeding mechanism D and the feeding mechanism A.

As the roller 65 turns, it imparts a reciprocating motion to the link 34 and the rack 35 that is transmitted to the plate 16 for feeding disks 10 into the rollers 13 in synchronism with the movement of the plunger mechanism B. As each successive disk passes through the rollers 13, it crowds the preceding disk into the die 55 below the ram 59.

In the operation of the feeding mechanism, a pile of disks 10 are placed between the supports 7 and 9. The supply of disks 10 may be renewed continuously without interrupting the operation of the feeding mechanism. As the plunger mechanism B is operated, the reciprocating motion is transmitted to the rack 32 and the rack 14, with a result that with the stroke of the latter, the lower disk 10 is advanced into engagement with the feed rollers 13.

By reason of the gripping action of the ports 23 and the yieldably mounted gripper 25, each advancing disk 10 is smoothed and held in firm engagement with the plate 22 over which it is advanced. By reason of the location of the suction gripper 24, the advancing edge of each disk 10 is firmly held in position to be positively engaged by the rollers 13 upon the initial engagement therewith, thereby eliminating any tendency for the feeding mechanism to get out of step with the plunger mechanism B, or to injure the edges of the disks 10 by improved engagement with the rollers 13.

We have provided a feeding mechanism for supplying paper disks to a can making machine that is characterized by the use of a vacuum system for insuring that each disk shall be brought into positive engagement with the feeder rolls, thereby eliminating any unnecessary loss of time in the feeding operation due to failure of the feeding rolls to immediately engage the advancing disks. At the same time, a positive feed insures perfect synchronism between the operation of the feeder rolls and the plunger to which the disks are fed. Provision is made for using the feeding mechanism for disks of different diameters by providing plates of different lengths and radii of curvature corresponding to the curvature of disks of different diameter, and an adjustable table is interposed between the feed rolls and the plunger. Another important feature of our invention is the lug that ruffles the stack of disks during each feeding operation, thereby freeing the lower disk preparatory to disengagement with the feeding plate. The positioning of the gripper in close proximity to the feed rolls also assists in insuring positive feed action. The provision of a vacuum system in connection with feed mechanism removes any dirt or lint that may be freed from the disks and the accumulation of which might impair the feeding operation.

While we have described our invention in

connection with the feeding of paper disks to paper can forming machines, it is to be understood that it is adaptable for uses in connection with materials other than paper and with machinery other than can forming machinery, and that the use of the feeding mechanism for such purposes is contemplated without departing from the scope of the appended claims.

10 We claim:

1. In a suction gripper, a body portion having a port therein adapted to cooperate with material passing the gripper, and resilient means for advancing the body portion into engagement with the material passing thereover.
2. In a feeder mechanism, the combination with a base member and a pair of feed rolls, of a material supporting table comprising a plurality of fingers extending outwardly from the base member and a body portion having fingers intermeshing with the fingers extending from the base member and means for adjusting the relative positions of the base and body.
3. In a feeder mechanism for supplying blanks to a head forming machine, the combination with a continuously driven roller and means for periodically delivering a single blank to the rollers, and means for guiding the movement of the blanks past the roller and directing a preceding blank into engagement with the head forming machine.
4. A feeding table comprising a rack movable longitudinally thereof, a plate carried by the rack for engaging material and a recess, a slot in the table, connecting means between the rack and plate movable in the slot, and a chamber formed in the feeder bed surrounding a portion of the slot, the roof of the chamber being provided with a plurality of ports disposed along the path of movement of the material and means for creating a partial vacuum in the chamber whereby the material is held in firm engagement with the table during the movement of the plate.

In testimony whereof we have hereunto set
50 our hands.

GEORGE O. FROSTAD.
JAMES E. ANNEN.
